UNITED STATES PATENT OFFICE.

PIERRE ANDRÉ FAVRE, OF CROSNE, FRANCE.

MACHINE FOR WORKING CYLINDRICAL MEMBERS OF FUSIBLE MATERIAL.

Application filed November 14, 1925, Serial No. 69,139, and in Belgium December 19, 1924.

The invention relates to machines for working cylindrical members of fusible material, and it more particularly relates to those for making serum bulbs from glass tubes or rods.

Its object above all is to render these machines such that they answer better to the various requirements of industrial practice.

It consists chiefly in providing machines of the type in question with prehensile members adapted to seize at a number of equidistant points and to hold the cylindrical member to be worked. These machines, if they are intended for example to carry out work upon a glass rod in order to make serum bulbs also comprise means which are automatic or otherwise such that: (1) the glass is softened over a predetermined part in each of the spaces comprised between the prehensile members, the number of which members is a function of that of the bulbs which the same glass rod may provide; (2) the prehensile members are spaced equal distances apart from the centre of the arrangement they form, drawing out the softened parts of the rod; (3) the rod is cut at the drawn-out portions and this is either done while the said rod is in the prehensile members or after it has been withdrawn from them; (4) the said rod, having been either only drawn out or drawn out and cut off, may be removed from the prehensile members; (5) the latter are returned to their original positions; (6) a new glass rod may be introduced into the said prehensile members.

It consists, apart from this main arrangement, in certain other arrangements which are employed preferably at the same time and are described more fully hereinafter.

The invention will more clearly be understood from the description hereinafter given in connection with the accompanying diagrammatic drawings which description and drawings are given by way of example.

Figures 1 and 2 in these drawings illustrate to different scales, an elevation of a bulb, a cross section of a part of a machine for making serum bulbs and constructed according to the invention.

Figure 3 shows to the same scale as Figure 2 a detail which is not shown completely in the latter figure.

Figure 4 shows in the same way as Figure 2 a detail constructed in another manner than that shown in the latter figure.

The machine consists of the following:

A frame 1 of suitable form to serve as a support for the members enumerated below; (1) a horizontal shaft 2 journalled longitudinally, upon which are mounted fixed pulleys 3 and loose pulleys 4, with a belt 5 driven by a motor 6 which is preferably electric; (2) as many equidistant prehensile members 7, plus 2, as the glass rod can give 60 bulbs, with parts of internal diameter equal to the external diameter of the body of these bulbs, which prehensile members 7 are arranged at the same height in planes perpendicular to the axis of the shaft 2. Each 70 comprises two plates perpendicular to the said axis guided by one or more sliders 8 parallel to the latter. The plates are freely traversed towards their lower part by the said shaft, and towards their upper part 75 by two cylindrical apertures facing each other and between which a ring 9 is adapted to turn. The ring 9 is provided with two arms 10 pivoted to it by one of their ends and acted upon by a spring 11 which tends to direct the one towards the other, and their other ends towards the axis of the ring; the whole being such that the prehensile members 7 being assumed to be in place, the glass rod 12 may be made to enter from the top and be held between the free arms 10 in the position for which its axis and that of the ring coincide with each other, by forming in the upper part of the plates, grooves 85 which are sufficiently large to allow the rod 90 to pass; by breaking the ring 9; by arranging for the rod 12 after it has entered into the grooves in the plates, to pass between the arms 10; and by terminating the said arms 95 by claw members adapted to seize the rod when it is coaxial with the said ring; (3) a means adapted to allow a movement of rotation at a predetermined speed to be transmitted by means of the rotatable shaft 2 to the rings 9, for example by mounting upon the shaft 2 for each prehensile member a toothed wheel 13, forming, with the ring 9 a broken toothed wheel of the same diameter as the wheel 13 and in connecting these two toothed wheels together by as many toothed 100 wheels 14 as are necessary to overcome the dead point produced by the broken part of the ring; (4) a means adapted to allow the prehensile members 7 to be moved to either side of the centre of the arrangement they form by amounts which vary but which are 105 equal for each position; the said means being

110

formed advantageously by making use of toggle levers 15 the joints of which, where the branches cross, are formed by vertical pins 16 fixed respectively to the lower part 5 of the prehensile members 7 and having their ends actuated in a manner indicated herein-after by two racks 17 and 18 respectively, which racks are parallel to the axis of the shaft 2, it being understood that the racks 10 may be replaced by links acting upon the toggle levers, that the prehensile members 7 may be actuated separately by means of members actuated by cone pulleys, that each prehensile member may be displaced by a 15 rack, the different prehensile members being actuated by gearings of different diameters by compressed air pistons; (5) a hand controlling lever 19 with two arms (Fig. 3) pivoted to a fixed shaft 20, one of 20 the arms of which in the form of a segment is adapted to raise one of the arms of a lever 21 also pivotally connected to a fixed shaft 22; a rod 23 connecting the lever 21 to a ratchet wheel 24 by means of an arm 25; (6) an inclined surface 26 upon which slide two endless chains 27 adapted to be driven by a shaft 28 upon which is fixed the ratchet wheel 24, the chains being provided with teeth between which are held the glass 30 rods 12 the whole in such a way that the teeth are successively brought above the grooves in the prehensile member 7 and that each glass rod falls at each operation in the 35 said grooves; (7) a lever 29 (Figure 3) actuated by the lever 19 in the second part of its stroke by means of a broken ring 30, which is connected to a double arm 31 which is pivotally connected, one of the ends of 40 which arm supports a rod 32 which when actuated exerts a sufficient pressure upon the glass rod 12 which has previously fallen in the grooves of the prehensile members 7 and compels it to enter the claws of the arms 10 and to take up a correct position even if the 45 glass rod is not quite straight; (8) a horizontal shaft 33 journalled in the frame in a direction which is parallel to the shaft 2 and upon which are mounted, fixed to it, a sleeve 34 integrally attached to the arms 35 and 36 50 connected in such a way, one to the key 37 of a gas tap, the other to that of an air tap (hidden by the first one) that when the said arms are raised the said taps are opened and vice versa; an operating lever 38 allowing this sleeve to be rotated in the manner indicated above; another sleeve 39 (Figures 1 and 2) provided with a lever connected to a bell device 40 which this lever brings back 55 into its original position when the sleeve 34 is raised by means of the hand lever 38, the action of the sleeve 33 upon the sleeve 39 being only exerted in one direction, the one mentioned above; (9) as many blow pipes 41 with as many blow burners for these blow 60 pipes as there are spaces between the pre-

hensile members 7, the burners being interposed each at an equal distance from two prehensile members, pivotally connected to the frame and controlled by sets of levers 42 themselves controlled by the lever 38 and the 70 shaft 33 so that the said blow pipes may be displaced normally towards the axis of the rod which is assumed to be in place in the said prehensile members, which blow pipes may be lighted or extinguished by opening 75 or closing the channels or carburant or air by oscillating the controlling lever 38 in one direction or the other; (10) a toothed wheel 43 mounted upon a shaft 44 (Fig. 1) and journalled perpendicularly to the axis of the 80 shaft 2 and rotated continuously by the motor 6 through a system of belts and corresponding pulleys suitably arranged to provide the necessary reduction in speed; (11) two shafts 45 parallel to the axis of the wheel 85 43 and journalled in the frame symmetrical- 90 ly relatively to the vertical plane passing through the said axis to the left and to the right of the said plane (assuming in the following description that the left and the right 95 of the machine are understood for everything which is shown in Fig. 1 when it is looked at from the front to the left and to the right of the said plane), each of these shafts 45 having loosely mounted upon them a toothed wheel 46 engaging with the wheel 43 and attached to them a toothed wheel 47, the two wheels 47 engaging with the racks; 100 two other toothed wheels of the same diameter being arranged as shown in Fig. 1 to the right and to the left of the wheels 46, connected by reduction gearing to the shafts 45 which rotate them at half speed, which additional wheels are adapted in the case when the machine comprises a very large 105 number of prehensile members to act upon other racks which actuate the toggle levers to which they would be connected, on each side and at a point equi-distant from the corresponding end of the said levers and of 110 their central axis, which arrangement comes under those mentioned above with reference to the various methods of extension of the levers; (12) a means adapted to render the righthand toothed wheel 46 integral with its shaft 45 which may be obtained in various ways for example, by making use of an ordinary sleeve clutch 48, with a return spring 49, adapted to be driven in trans- 115 lational motion by one of the ends of a pivoted hand lever 50 this lever having the function in one direction alone (the one in which it is lowered) of impressing a fraction of a turn upon the shaft 33 by means of a stud and in doing this of lowering the lever 38 and its integrally attached sleeve 34 which have been previously raised; (13) a means 120 adapted to enable the same result to be obtained for the lefthand toothed wheel 46 but at other moments than for the righthand 125 130

wheel 46 which result may be obtained in a similar way, that is to say with a pivoted lever 51 (Fig. 1) and a clutch sleeve; (14) a pivoted lever 52 arranged in such a way that it strikes the lefthand rack by striking against it acts upon the bell device 40 connected by a pivoted link mechanism to a rod ending in a fork 53 engaging over the belt 5 and then effects the disengagement of the shaft 2; (15) a sort of locking device adapted to enable, when the disengagement of the shaft 2 has been completed, this shaft to be rendered stationary in the position for which the rings 9 are placed as shown in Figure 2; this locking device is formed by a pivoted lever 54 (Fig. 1) connected to the bell device 40 in such a way that when it is driven by the rodding it puts under tension a spring 55 attached to a device 56 provided with an arm 57 which then exerts a slight pressure upon a ring 58 attached to the shaft 2 and in which is formed a notch in which lodges the arm 57 as soon as the shaft 2 by turning brings the said notch opposite the said arm; (16) a hand controlling lever 59 connected by pivoted links 60 and 61 to an arm 62 integrally attached to a shaft 63 journaled in the frame parallel to the shaft 2; the shaft 63 is therefore also rendered integral with a member carrying a rod 64 parallel to the shaft 2 running the whole length of the prehensile members 7 and adapted when the lever 59 is lowered to encounter an arrangement of levers 65 and 66 with link 66 interposed (an arrangement by prehensile members) pivoted to two fixed shafts 68 and 68¹ and to cause it to oscillate in such a way that each lever 66—which terminates in a kind of shuttle 69 itself of such a form—then engages its shuttle between the claws of the corresponding arms 10, opens them out, raises the glass rod 12 (once the latter as hereinafter shown has been drawn out) and carries it upon an inclined surface 70 where it rolls; each arrangement of levers 65 and 66 once it has acted in this way is returned to its original position by the action of a rod 71 parallel to the preceding one and of the same length, integrally attached to a shaft 72 journaled in the frame and connected to the shaft 63 by a set of pivoted levers 73 such that when the controlling lever 59 is raised the said rod 71 presses upon the levers 65 causing the shuttles 69 to pass between the claws 10 in the opposite direction to the preceding one; (17) a lever device of which for each pair, one of the branches 74 is attached to the inclined surface 70 and the other movable one 75 is mounted upon a shaft 76 journaled in the frame parallel to the shaft 2 and controlled by the shaft 33 to which it is connected by an arrangement of pivoted levers and links 77, 78 and 79; (18) and a travelling band 80 which receives its movement from a suitable arrangement of belts.

The machine thus formed and suitably mounted, operates as follows:

With one finger of the left hand the controlling lever 19 is pulled and lowered (this lever as well as the other controlling levers 70 being arranged so that they can easily be operated, as hereinafter described, when facing the machine).

This lever acts in the first half of its stroke upon the lever 21 which, through the medium of the members 23 and 25 causes the ratchet wheel 24 to make a fraction of a turn which produces a forward movement of the endless chains 27 which allow a glass rod to fall in the grooves in the prehensile members 7; the sector of the lever 19 then ceases to act upon the distributing device and holds it in the position in which it is when the glass rod has fallen, and in the second half of its stroke the lever acts upon the lever 29 which, through the medium of the member 31 compels the glass rod to enter between the claws of the prehensile members 7 (inserting device).

The lever 19 is then released and returns to its original position under the action of suitable springs such as the one shown in Figure 3. The distributing device and the inserting device return in their turn to their original position.

The same hand, the left one, which operates the lever 19, seizes the controlling lever 38 and raises it in order to rotate it through 90° about its axis.

This lever 38 drives the shaft 33 and the sleeve 34 the effect of which is to:

1. Actuate the scissor device in such a way that the movable branches 75 of these levers close upon the fixed branches 74 and cut the slender portions which connect the bulbs together in the chain formed in the preceding operation; the bulbs which are detached from each other then roll upon the inclined surface 70 to the travelling band 80 which carries them to one end of the machine where they are collected in a box provided for the purpose;

2. Open by means of the arms 35 and 36 the gas and air taps which supply the blow pipes 41;

3. Actuate by means of the sleeve 39 the bell device 40 in the direction in which the belt 5 passes from the loose pulley 4 to the fixed pulley 3;

4. Remove the arm 57 from its engagement in the notch on the ring 58;

5. Bring the blow pipe device into place.

The blow pipes act the shaft 2 is released and turns, transmitting its rotation to the glass rod 12 through the medium of the gears 13, 14 and the toothed ring 9.

The glass rod is then heated at the suitable parts comprised between the prehensile members 7.

As soon as the said parts have reached the

desired degree of fusion the operating lever 50 is lowered with the right hand.

The action of this lever is as follows:

1. It causes the shaft 33 to make a partial revolution of 90° in the opposite direction to that in which it is moved when the lever 38 is raised and in making this movement it closes the gas and air taps so that the blow pipes are extinguished the pilot flames 10 alone remaining alight for a subsequent operation.

2. It causes the blow pipe device to move back thus allowing the prehensile members 7 to be displaced.

15 3. It brings the scissor device back into its original position.

4. It brings into engagement the clutch arrangement which causes the right hand toothed wheel 46 to become integral with its 20 shaft 45. This wheel then transmits rotation to the corresponding wheel 47 which acts upon the two racks by means of a suitable arrangement of gears and separates them from each other in such a way that the toggle lever opens, the effect of which is to cause the prehensile members 7 to move away from each other and consequently the softened parts of the glass rod comprised between the 25 said prehensile members to be drawn out.

30 Before arriving in this extreme position which enables the prehensile members to be displaced, the left hand rack, by means of the lever 52 and the pivoted link mechanism of which mention has been made, engages the belt 5 upon the loose pulley 4 the 35 effect of which is to stop the shaft 2 and by means of the locking device the said shaft 2 to be rendered stationary in the position for which the ring 9 is arranged as shown in 40 Figure 2.

When the racks reach their extreme position the pressure of the hand upon the lever 50 must cease.

45 The necessary time is allowed for the glass to cool down.

Then, with the left hand, the lever 59 is lowered the effect of which is, by means of the extraction device 60 to 69, to remove the glass rod from the claws of the arms 10 and 50 to carry the chain of bulbs upon the inclined surface 70 upon which it rolls as far as the fixed branches 74 of the scissor levers which stop it in order to cut it in the following operation.

55 When this operation is completed the lever 59 is released and in falling back it impresses the opposite movement upon the device 60 to 69.

60 The operating lever 51 is then seized with the right hand and lowered through 90°.

The action of this lever is limited to the corresponding engagement and the securing of the toothed wheel 46 on the left to its shaft 45 the effect of which is to transmit 65 the rotation of the wheel 48 to the left hand

wheel 47 which sets upon the racks and brings them towards each other, thus closing the toggle levers while bringing as a consequence the prehensile members 7 towards each other to the points at which they were before being separated.

And a next operation is commenced.

The machine thus constructed may operate with only the hand control members. But it is clearly understood that these members may be replaced by automatic means which would obviate wholly or in part the necessity for these hand controls, for example by means of a wheel provided with suitable cams which would be arranged on its periphery, a single turn of which wheel would produce in succession the operations enumerated above, the cams raising levers similar to those described which are moved by hand.

The drive may be for example electro-mechanical pneumatic, or hydraulic.

Further, each prehensile member described may be replaced by a prehensile member of another type, for example by the one shown in Figure 4.

This other prehensile member comprises two wheels 81 upon which can rest freely a glass rod 12 which has passed through grooves provided for the purpose formed in the plates of the said prehensile member, the said wheels being driven, for example, by friction, rotating in opposite direction, by means of a wheel which slides by means of a long key upon the shaft 2.

The glass rod having once been placed upon the wheels 81 is held there by the pressure of another wheel 83 fixed to a pivoted lever 84.

For the remainder: the distribution of the glass, extraction, cutting, etc., the method of procedure will be the same as with the preceding prehensile member, these prehensile members only differing from each other in the manner in which the glass rod is held and made to turn.

It is understood that each lever 66 may be employed, itself or a similar lever, on the first prehensile member as well as on the second so as to exert, upon a corresponding given portion of the glass which has been previously softened, a pressure which during the drawing out operation is adapted to cause the portion which is drawn out to be narrowed.

As it is seen, whatever be the arrangement adopted the bulbs are obtained at the same time upon one single glass rod. These bulbs are cylindrical with two points and may comprise a contraction on each of their drawn out portions, which contraction is provided so that bulbs with a flat end and a contraction may be obtained with another machine conjugated with the present one.

It goes without saying and it also is clear from the above description that the inven-

tion is not limited in any way to this of its methods of application nor to those of the forms of construction of its various parts which have been more particularly described above; it includes on the contrary all modifications, for instance those in which, in order to obtain the various operations of which mention has been made, the members adapted to produce this result would be different and arranged in different ways from those which have been described.

What I claim is:

1. A machine of the class described comprising in combination gripping means for holding a rod of fusible material at a plurality of points, means for heating said rod intermediate said points, means for moving said gripping means so as to draw the fusible material and means for cutting the rod.
2. A machine of the class described comprising in combination gripping means for engaging a rod of fusible material at at least three points, means for heating said rod intermediate said points, means for moving the gripping means while maintaining equal distances between the points at which it engages the rod, and means for cutting the rod at a plurality of points.
3. A machine of the class described comprising in combination at least three members arranged so to grip a rod at a corresponding number of points, means for heating a rod in the spaces between the prehensile members, means for moving the prehensile members while maintaining equal distances between them and means for cutting the rod at a plurality of points.
4. A machine of the class described comprising in combination at least three prehensile members adapted to seize a rod a corresponding number of points, means for heating said rod in the spaces between the prehensile members, means for moving the

prehensile members longitudinally with respect to the axis of the rod, means for cutting the rod, means for removing said rod from said prehensile members, means for moving said prehensile members back to their initial position and means for placing a new rod in position to be held by the prehensile members.

5. A machine of the class described comprising in combination at least three prehensile members arranged to seize a rod at a corresponding number of points, means for heating said rod in the spaces between the prehensile members, means for moving said prehensile members while maintaining equal distances between them, means for removing said rod from the prehensile members, means for moving the prehensile members back to their original position, means for placing a new rod in position to be held by the prehensile members, and means for cutting the rod.

6. A machine of the class described comprising in combination at least three prehensile members arranged to seize a rod of fusible material at a corresponding number of points, means for heating said rod at at least two points, and means for moving said prehensile members in a longitudinal direction with respect to the rod axis.

7. A machine of the class described comprising in combination at least three prehensile members arranged to seize a rod of fusible material at a corresponding number of points, means for heating said rod at at least two points located between the prehensile members, and means operable to move the prehensile members longitudinally with respect to the rod axis while maintaining equal distances between said prehensile members.

In testimony whereof I have signed my name to this specification.

PIERRE ANDRÉ FAVRE.
